United States Patent Office.

PINDAR F. COOLEY, OF PITTSFIELD, MASSACHUSETTS.

Letters Patent No. 81,754, dated September 1, 1868.

IMPROVED WHIP-HANGER.

The Schedule referred to in these Letters Patent and making part of the same.

TO ALL WHOM IT MAY CONCERN:

Be it known that I, PINDAR F. COOLEY, of the town of Pittsfield, in the State of Massachusetts, have invented a new and improved Mode of Hanging, Holding, and Preserving Whips; and I do hereby declare that the following is a full and exact description thereof, reference being had to the accompanying drawings, and the letters of reference marked thereon, in which—

Figure 1 represents a perspective view.

Figure 2 is a vertical view of a section showing whips in the notches.

Figure 3 is a cross-section of rim through notches, with whips inserted.

The nature of my invention consists in this:

I form of wood or metal (cast or struck) a circular, oval, square, or other form rim, from three to four inches wide, (according to the nature of the material used,) and into this rim, from either or both edges, I provide V-shaped notches to a depth, into the rim, varying from one to one and a half inch. The upper surface-line of the rim, commencing at the inner and the outer edges, curves down until past the termination of the notches, when they meet in the centre of the rim. The outer circumference of the rim may vary from twelve inches to six feet, according to the capacity desired for holding whips.

This notched rim is furnished, on its upper surface, with three or more eyes, to receive a corresponding number of supporting-rods or chains. The said rods or chains connect into a common swivel, provided with an eye or link, by which the whole is suspended from the ceiling by a hook, or by a crane from the wall.

To put in place and suspend whips as intended, their snappers are placed into the notches, and pressed slightly towards the centre of the rim, and drawn down; and when this action is being performed, the curviform-surface line of the rim at the notches tends to draw the whip tighter into the notches, thus dispensing with extraordinary care and attention while hanging the whips. And with this curviform-surface line, three and four whips (the smaller-sized placed in first) can be suspended from one notch, which it would be impossible to do with a flat-surface line.

The advantages of my invention are these;

First, in a small space, say the area of a space of only eighteen inches diameter, from eighty to two hundred whips may be suspended, without one whip interfering with the others.

Second, though the whips suspended may be many in number, they may be arranged and lotted according to price-list, and their several grades preserved distinct by the same whip-suspender.

Third, the curviform upper-surface line not only aids a person to fix the whip in its notch, but aids its removal by the peculiarity of that line.

Fourth, suspended aloft, and revolving by means of the swivel, whips on any side, and of any grade, may be presented for inspection instantly.

Fifth, whips so suspended cannot be bent when thus held, and if bent when out, will tend to straighten by their weight when again suspended.

To enable those skilled in the art to make and use my invention, I will proceed to describe its construction and operation, by reference to the drawings forming a part of this specification, and to the letters of reference marked thereon, the same letters referring to like parts.

A A, figs. 1, 2, and 3, represent a rim constructed of wood or metal, in a circular, square, oval, or other form. The upper-surface line of this rim is curviform from both the outer and inner edges, as shown in fig. 2, by *g. g.* This rim, A, is made of such width as to admit having cut into it, from both its outer and inner edges, V-shaped notches *n n n*, to a depth varying from one to one and a half inch, and yet leave sufficient material between the notches to insure strength.

At suitable points on the upper side of the rim are placed eyes, *e e e*, from which start the suspending-rods *o o o*, or their equivalents, which rods or chains connect in a common swivel, *c*, provided with an ordinary eye or link, by which the whole is suspended from a hook fastened into the ceiling, or from a crane starting out from the wall.

When the whips are to be suspended or held, their snappers, $s's's$, are placed and drawn into the notches $n'n'n$, as shown in figs. 2 and 3, from which notches the whips will become pendent when left to themselves. When two or more whips are to be suspended from the same notch, as shown in figs. 2 and 3, the smaller-sized snappers are inserted first, as s , which is followed by the larger, $s's''$.

Having described my invention, I do not claim the notch n of itself; but

What I claim, and desire to secure by Letters Patent, is—

1. The notch n with the upper curviform-surface line g , substantially as and for the purpose set forth and described.
2. The rim A, constructed circular, square, oval, or any other form, provided with the notches $n'n'n$, as described, and the supporting-rods $o'o'o$, or their equivalents, and all in combination with the swivel C, as and for the purpose set forth and described.

PINDAR F. COOLEY.
